UNITED STATES PATENT OFFICE.

EDWIN B. HIRSCH, OF NEW YORK, N. Y., ASSIGNOR TO DISPLAYCASE CO., INC., OF NEW YORK, N. Y., A CORPORATION OF NEW YORK.

DISPLAY-CASE CONSTRUCTION.

1,369,811.

Specification of Letters Patent.

Patented Mar. 1, 1921.

Application filed March 31, 1920. Serial No. 370,258.

To all whom it may concern:

Be it known that I, EDWIN B. HIRSCH, a citizen of the United States, and a resident of the city of New York, in the county of 5 Kings and State of New York, have invented certain new and useful Improvements in Display-Case Construction, of which the following is a specification.

This invention relates to certain improvements in the construction of display cases which are exhibited on sales counters of stores to display merchandise for hand sales and particularly relates to that type of such cases, in which a glass cover plate is movably mounted on the body part of the case to protect the merchandise contained therein.

It is an object of the present invention to provide a casing which is most simple 20 in its construction and consists of a minimum number of parts.

It is another object of the invention to provide a new mounting for the glass cover plate which insures its protection against 25 accidental breakage in handling.

It is a further object of the invention to provide a new easel-support for said cover plate of particularly simple construction and ease of operation.

With these and other objects in view the invention consists in certain novel details of construction and arrangements of parts hereinafter fully described and illustrated by the accompanying drawings and finally 35 pointed out in the claims.

In the drawings which form a part of these specifications:

Figure 1 is a side elevation of a display case with single cover-lid embodying the invention.

Fig. 2 is a plan view of the same display case seen in the direction of the arrows A—A of Fig. 1.

Fig. 3 is a part of a sectional elevation 45 taken on the line 3—3 of Fig. 2.

Fig. 4 is a sectional elevation taken on the line 4—4 of Fig. 2.

Fig. 5 is a detail sectional elevation on the line 5—5 of Fig. 2, showing the single 50 joint in the casing channel 1^a.

Fig. 6 is a detail plan of the corner shown in Fig. 5.

Fig. 7 is a detail elevation seen in the direction of the arrows 7—7 of Fig. 1 show-

ing the construction of the connecting rod 8 55 to frame 7.

Fig. 8 is a side elevation of a display case with double cover-lid, embodying the invention.

Fig. 9 is a plan view of the display case 60 shown in Fig. 8 seen in the direction of the arrows D—D of Fig. 8.

Fig. 10 is a sectional elevation taken on the line 10—10 of Fig. 8 showing the easel frame 7 folded for shipment. 65

Fig. 11 is a sectional side elevation on the line 11—11 of Fig. 9.

Fig. 12 is a side elevation of Fig. 10 showing the easel frame 7—8 in folded condition for shipment. 70

Similar characters of reference indicate corresponding parts throughout the various figures.

Referring to Figs. 1 to 7 of the drawings 75 1 represents the body part or casing of my display case with a single cover-lid. The four vertical sides of this casing are made from a single strip of sheet metal bent into channel shape to form the web 1^a, the top flange 1^b and the bottom flange 1^c. This 80 metallic channel-section surrounds the whole casing, being bent rectangularly at three corners and joined, preferably by soldering at the fourth corner as shown in Figs. 5 and 6 by means of the triangular flap 1^d. 85 The bottom of the casing is formed by a rectangular plate 2 resting on the flange 1^c. This plate is held in place by means of distance-pieces 3 which lean with one face against the back 1^a of the channel frame 90 and with the upper edges against the top flanges 1^b of the frame. The bottom plate 2 and the distance-pieces 3 are preferably made from hard, fibrous material, as wood or heavy pasteboard to be slightly resilient 95 and to remain in place by friction against the abutting faces.

The cover for the casing is formed by a rectangular metallic frame 4, made from a single strip of sheet-metal, bent into form 100 of a U shaped channel and preferably connected by soldering at one of its corners. The top flange of this channel frame 4 is covered by a layer of felt 5, cemented thereto and to this felt-cushion the glass cover plate 105 6 is cemented. The frame 4 is connected by means of hinges 4^a to the front side of the casing. Near the upper end of frame 4 a

rectangular wire frame 7 is swingingly held by means of the stub ends 7^a in apertures 4^c of said frame to form an easel support for the cover plate of the casing. The horizontal bar 7^a of this frame is provided at its center with a short sleeve 7^b. A similar sleeve 1^e is attached to the center of the lower flange 1^c of the front side of the casing. A wire connecting rod 8 is swingingly held 10 in this sleeve by means of a rectangular bend 8^a formed from the same wire. The extreme other end of connecting rod 8 is provided with a similar rectangular bend 8^b which is adapted to be shifted into the sleeve 7^b 15 of the frame 7, and in such position will hold this frame erected, in fixed relation, yet movably connected to the casing 1 and frame 4. The rear side 4^b of the cover frame 4 is provided at its center with a hinged latch 9, which can be joined to a corresponding latch block 9^a held at the center of the rear side of casing 1 and adapted to hold the casing locked to the cover plate 6 and frame 4.

20 The display case illustrated in Figs. 8 to 12 is of similar construction to the one hereinbefore described, excepting the cover, which consists of two lids 10 hinged together by means of hinges 11 and the hinge rod 12, whose downwardly bent ends 12^a are fastened preferably by soldering to the centers of the front and rear sides 1^a of the casing. On either side of the rod 12 a cover frame 4^c is fastened to the hinges 11 preferably by 25 soldering. The frame 4^c like frame 4 consists of a single strip of sheet metal, bent into the form of a U shaped channel, to the top flanges of which a layer of felt 5 is cemented, which forms a cushion for the 30 glass plates 10, which are cemented thereto. The rectangular easel frame 7 is hinged on this display case to apertures 16 in the web 1^a of the sides of the casing; in all other respects the wire frame 7 and connecting rod 8 and their fastenings are identical with those described for the single lid case shown in Figs. 1 to 7.

35 Display cases of the type herein described are generally placed on the counter or stores in a slanting position for the better exhibition of the merchandise therein contained, to the eyes of the public. Referring again to Figs. 1 to 7, the easel frame 7 held by connecting rod 8 to the casing, accomplishes this purpose. If the case is to be 40 opened to make a sale, the operator will open the latch 9 whereby the casing 1 drops to the supporting surface, swinging around the sleeve 1^e and taking the position indicated by the dash and dotted lines of Fig. 1. It will be seen that the frame 4 and cover plate 6 remain in slanted position supported by easel frame 7 and that the latter makes 45 only a small angular movement.

50 If a number of these cases have to be

packed and shipped the connecting rod 8 which consists of resilient wire, can be bent sufficiently so that the part 8^b leaves the sleeve 7^b of the easel frame as shown in Fig. 2 by dash and dotted lines whereupon the 55 easel frame 7 may be swung into such position that its bar 7^a leans against the bottom 2 of the casing as indicated in Figs. 8 and 12, which permits the whole display case with its cover plate to lie flat on a supporting 60 surface.

The display case illustrated in Figs. 8 to 12, provided with a double cover lid, each of which may be opened separately, will remain in slanting position when these lids 65 are opened, as the easel frame of this case is hinged to the casing 1 and either cover lid can be turned through an angle of 180 degrees, that the face of one glass plate comes to rest on the face of the other as indicated by the dash and dotted lines of Figs. 8 and 10. It is a particular advantage of the construction of this case, that the glass plates do not break when they are 70 violently thrown upon each other; which is 75 accomplished by the resiliency of the channel frames 4^c fastened to the under side of the glass plates with interposition of the 80 felt cushion. Another advantage of the 85 present invention is its simplicity of construction, as the channel frame of the casing 1 as well as the channel frame 4 of the 90 cover consists of single strips of metal whose 95 flanges only are cut, to be mitered at the 100 corners of the casing and either frame is held 105 together by a single soldering joint; while the bottom plate 2 is held in place by the distance-pieces 3, which press against this plate and the flanges 1^b without any other means of fastening.

Having thus described my invention, what I claim as new and desire to secure by Letters Patent is:

1. In a display fixture of the kind described, a casing whose sides are formed by a continuous strip of metal of channel shape and joined at one of the corners of said casing to form a frame and a bottom plate held within said channel frame by means of distance-pieces pressing against said plate and one flange of said channel frame.

2. In a display fixture of the kind described a casing adapted to hold the displayed goods, the metallic sides of said casing being provided with parallel horizontal flanges along their top and bottom edges, a bottom plate resting on the lower row of flanges and a fibrous lining on the sides of said casing extending from said bottom plate to the upper flanges and forming means to retain said bottom plate in stationary position in said casing.

3. In a display fixture of the kind described, a casing formed by a bottom plate and side plates, a frame resting on the top

edges of said side plates, hinged to said casing and consisting of a resilient metallic channel and a cover plate held above said channel by means of a strip of fibrous material fastened to said frame and to said cover plate.

4. In a display fixture of the kind described a casing formed by a bottom plate and side plates, a frameless glass cover plate 10 whose unprotected edges extend beyond the outer edges of said side plates rotatively connected to said casing and metallic resilient means held by the lower side of said cover plate, resting on the top edges of 15 said casing.

5. In a display fixture of the kind described, a casing formed by a bottom plate and side plates, a cover for said casing hinged to one side thereof, a frame rotatively held on said cover near its free end 20 and locking means connected to said casing and removably fastened to said frame to hold said frame in upright position.

6. In a display fixture of the kind described a casing adapted to rotate about its 25 lower front edge, a cover above said casing adapted to swing about the lower front edge of said casing, means to support said cover in opened position above said casing and a locking bar hinged to said casing and slidably connected to said supporting means to 30 form a detachable connection with said casing.

7. In a display fixture of the kind described a casing adapted to rotate about its 35 lower front edge, an easel-support rotatively attached to said casing and adapted to support the rear part of said casing in elevated position and a resilient locking bar hinged and fastened to said casing formed to provide at its free end a detachable connection to said casing by a temporary deformation of 40 said bar in perpendicular direction to the rotative movement of said bar.

EDWIN B. HIRSCH.
